PLATING CARRIER DRIVE FOR KNITTING MACHINES

Ubaldo Pianta, Milan, Italy, assignor to Società Italiana Ernesto Breda Per Costruzioni Mecaniche, Milan, Italy, a firm

Application April 17, 1947, Serial No. 742,182
In Italy April 3, 1946

Section 1, Public Law 690, August 8, 1946
Patent expires April 3, 1966

SEARCHED PLACED CLAIM 3 Claims. (Cl. 66—126)

1

In present straight-bar machines for hosiery and the like, and particularly in straight-bar Cotton's machines, the drive of the plating carriers was attained by several actuating slides or slippers, or by other complicated devices.

The same result is obtained more simply by the present invention with a single slide, by means of an automatic recuperation device.

According to the invention, the slide bears one of the carriers and a slipper bearing the other carrier is mounted longitudinally slideable on said slide; at the two ends of the slide stroke means are provided to return the slipper to a predetermined position relative to the arriving slide and means to hold said slipper stationary while the slide starts its reverse movement.

In order to better explain the above invention, an embodiment given by way of example is now described with reference to the attached drawing, in which:

Fig. 1 is a front view of the device at the beginning of the forward stroke;

Fig. 2 is a plan view of Fig. 1;

Fig. 3 is a front view of the device at a certain phase of the forward stroke;

Fig. 4 is a plan view of Fig. 3;

Fig. 5 is a front view of the device at the end of the forward stroke.

In this device a reciprocating bar 1 is slidably mounted in frame members 1a.

The reciprocating bar 1 is integral with the friction slide 2 on which the carrier 10 is fixed. The slipper 3 bearing the carrier 9 is placed in sliding guides on the slide 2.

When starting the motion, the bar 1 drags the slide 2, while the slipper 3 is held by the lever 6; thereby, the carrier 9 starts with some delay with respect to the carrier 10. The amount of this delay is established by the position of the nose 11 placed on the slide 2; actually said nose raises the lever 6 against the action of respective springs 12 carried by the frame members 1a whereby to leave the slipper free when the latter has reached the predetermined delayed position, so that the carriers 9 and 10 take the relative positions shown in Fig. 3.

Said positions are maintained during the whole of the remaining portion of the stroke of the bar 1 and slide 2.

At the end of the forward stroke the amplifying lever 4, pivoted on the slide 2 and having the nose 4' of its major arm 4" engaged in the depression 3' of the slipper 3, pivots owing to the reaction of the minor arm 4''' on the screw 5';

2

due to said swinging of the lever 4, the slipper 3 is forced to move recovering the former position of the carrier 9 with respect to the carrier 10.

The lever 6 engages the slipper 3 automatically, due both to gravity and action of the flat spring 12.

At one side of the slipper 3 there is provided at each end a pair of adjacent lugs 15 forming a notch 16 between each pair. Carried by the lever 4 is a coiled spring 17 having arms 18 projecting towards the end of the slipper. Each arm carries a head 19 provided with a nose 20 of a size and shape to fit a respective notch 16. The distance between the noses 20 is substantially equal to the distance between the pairs of lugs 15 as indicated in Fig. 2 and biassing of the lever 4 will cause a nose to engage the respective notch 16 as in Fig. 4. This construction forms a snap means for latching the slipper to the slide.

At the beginning of the backward stroke of the bar, the same steps as in the forward motion are repeated, the lever 6' acting in the similar way as the lever 6 so as to let the carrier 9 start with some delay with respect to the carrier 10, with consequent recuperation at the end of the stroke of bar 1, and so on for each forward and backward stroke of the same. As the slipper is reciprocated the arm 4''' of the lever 4 contact with adjustable screw stops 5, 5', which effect proper biassing of the lever to effect movement of the slipper 3 on the slide 2.

Obviously, many of the constructional details described above by way of example may be either replaced or modified without exceeding the scope of the invention.

I claim:

1. In a plating carrier drive in a straight-bar knitting machine for hosiery and the like, a slide, a slipper reciprocable longitudinally on said slide, a pair of spaced frame members between which said slide reciprocates, latch levers each pivoted to a respective frame member and each having a trip arm, and trip lugs at the ends of said slide engageable with the trip arms upon movement of the slide a predetermined distance from the ends of its reciprocation, other lugs on the slipper engaged by said latch levers at the ends of the reciprocation of said slide, the engagement of said trip arms with said trip lugs freeing the latch levers from the lugs on the slipper.

2. In a plating carrier drive in a straight-bar knitting machine for hosiery and the like, a slide, a slipper reciprocable longitudinally on said slide, a pair of spaced frame members between which

said slide reciprocates, latch levers each pivoted to a respective frame member and each having a trip arm, trip lugs at the ends of said slide engageable with the trip arms upon movement of the slide a predetermined distance from the ends of its reciprocation, other lugs on the slipper engaged by said latch levers at the ends of the reciprocation of said slide, the engagement of said trip arms with said trip lugs freeing the latch levers from the lugs on the slipper, and coacting snap means latching the slipper against movement on the slide during reciprocation of the slipper between said latch hooks.

3. In a plating carrier drive in a straight-bar knitting machine for hosiery and the like, a slide, a slipper reciprocable longitudinally on said slide, a pair of spaced frame members between which said slide reciprocates, latch levers each pivoted to a respective frame member and each having a trip arm, trip lugs at the ends of said slide engageable with the trip arms upon movement of the slide a predetermined distance from the ends of its reciprocation, other lugs on the slipper

15

engaged by said latch levers at the ends of the reciprocation of said slide, the engagement of said trip arms with said trip lugs freeing the latch levers from the lugs on the slipper, spaced 5 pairs of lugs on said slipper providing notches therebetween, a lever pivoted to said slide, a spring carried by said lever and having oppositely extending arms, means carried by said lever arms engageable in said notches, and stops carried by 10 said frame members and biasing the last mentioned lever at the ends of the reciprocation of the slide.
